SAMPLE WASHER

Alfred G. Lewis, Linden, N. J.

Application July 2, 1942, Serial No. 449,525

3 Claims. (Cl. 209—237)

The present invention is directed to a suitable means for washing and drying samples of cuttings obtained in drilling wells.

In the drilling of bore holes, it is customary to obtain samples of cuttings at regular intervals in order to obtain a geological record of the formations being traversed. A usual drilling operation involves the circulation of a drilling mud or fluid, the circulating fluid removing cuttings from the lower end of the bore hole to the surface of the earth. Accordingly, the samples of cuttings collected at the surface are wet and contaminated with mud.

It is an object of the present invention to devise a means suitable for washing and drying samples of formations with a minimum of attention.

Other objects and advantages of the present invention may be seen from the following description taken with the drawing in which

Fig. 1 is an elevation, partly in section, of a preferred embodiment of the present invention; and

Figs. 2, 3 and 4 are fragmentary views showing in greater detail parts of the device illustrated in Fig. 1; and

Figs. 5 and 6 show other suitable embodiments of the sample container used in the assembly.

The device of the present invention may be described briefly as comprising a prime mover arranged to rotate an eccentrically arranged screen container in a bath of water for cleansing the sample, and a cylindrical container provided with heating means for drying the sample. In the drawing, numeral 11 designates a suitable prime mover such as electric motor 11, numeral 12 designates the water bath with container 13 arranged therein, and numeral 14 designates the sample dryer.

The bath 12 of the washing device is provided with a suitable inlet 15 leading into an upper portion thereof and a valve controlled outlet 16 attached to a lower portion thereof. A shaft 17 is arranged in the bath connected for rotation by motor 11 and another shaft 18 is attached to the other end of the container. Rectangular sections are cut out of both shafts 17 and 18 to accommodate the square axles 19 with which container 13 is provided. Suitable means, such as arcuate members 20 arranged on shafts 17 and 18 are provided for securing the washer axles 19 to shafts 17 and 18 and for releasing them at the option of the operator, as in Fig. 4.

The container 13 may be generally described as being in the shape of a capsule divided into

two sections along its longitudinal axis with an axle 19 secured to each section. The container is provided with a suitable hinge 21 and latch 22 for securing the two halves of the container together during the actual washing step. The arrangement of the axles on the container gives it an eccentric motion as it is rotated.

The drying mechanism comprises generally a cylindrical container 23 arranged for cooperation with a flanged circular member 24 which is arranged to be rotated by shaft 17. It will be seen that container 23 and member 24 are generally similar to a can fitted with a removable cover and member 24 will be designated as the cover for convenience in the following description. The portion of shaft 17 to which cover 24 is attached is tubular in section and is arranged for receiving a cylindrically shaped electrical heating element 25. The connections for furnishing power to this element run through shaft 17 to slip rings 26 where conventional carbon brushes 27 connect the slip rings to a source of power (not shown).

The heating element 25 is provided with a cylindrical cover 28 and extending from the free end of the cover to element 24 are a plurality of bowed elastic members 29 which serve to support container 23 when it is in position. A hinged cover 30 is provided in the side of the container with a suitable latching means 31. The ends of container 23 and member 24 are proportioned to allow the circulation of air from the exterior to the interior of the container. A preferred method of accomplishing this end is by providing the container with a plurality of ridges 32 for contact with the flange of member 24, the ridges allowing circulation between the container and the cover element.

The preferable manner of using the device of the present invention is as follows: A sample of cuttings is collected from the drilling fluid. Container 13 is removed from the tank, opened up, the sample placed therein, and the container latched in a closed position and secured to shafts 17 and 18. The water is then allowed to circulate through the bath and at the same time the motor is started to rotate container 13, the rotation of the container and circulation of water continuing until the circulating water no longer becomes muddy. Rotation of the container is then stopped, the container is removed from the bath, opened, cover 31 of the dryer opened and the sample transferred from the washer to the dryer. The dryer is then closed, heat applied to the heating element thereof, and the dryer rotated to remove moisture uniformly from the

sample. When the sample is dry, the container 23 may be pulled from the shaft and the sample removed therefrom.

Another embodiment of a container suitable for employment with the vat 12 is shown in Figure 5. In this embodiment a container 38 is divided into two longitudinal sections as in the embodiment precedingly described. In addition, a solid member 39 is removably positioned between the two sections to divide the container into two compartments. It will be evident that this embodiment allows two separate samples to be washed simultaneously.

Still another embodiment of a suitable means for holding the samples in the washing device is illustrated in Fig. 6. In this embodiment the container 36 is divided transversely into two sections which fit together by a friction joint 35. This joint also defines a suitable annularly shaped groove 36 arranged to retain circular solid member 37 in position. In this embodiment, as in the precedingly described embodiment, two samples may be washed simultaneously without danger of mixing them.

Having fully described and illustrated preferred embodiments of the present invention, what I desire to claim as my invention is:

1. A device adapted for washing samples comprising, in combination, a capsule shaped, perforated container, aligned stub axles secured to said container to make an acute angle of substantial size with the longitudinal axis of said container, a vessel for holding washing liquid, a pair of aligned spaced substantially horizontal shafts journaled to said vessel and means releasably engaging said shafts with said axles for rotatively supporting said container in said vessel.
2. A device in accordance with claim 1 in which said container is divided longitudinally and is provided with a longitudinally extending partition separating it into a plurality of zones.
3. A device in accordance with claim 1 in which said container is divided laterally and is provided with a laterally extending partition separating it into a plurality of zones.

ALFRED G. LEWIS.
